(57) **CLAIM**

The ornamental design for a vehicle body, as shown and described.

DESCRIPTION

FIG. 1 is a front, side and top perspective view of a vehicle body showing the new design, wherein the front, opposite side and top perspective view being a mirror image thereof; FIG. 2 is a side view thereof, the opposite side being a mirror image of that shown; and,

FIG. 3 is a rear, side and top perspective view thereof, wherein the rear, opposite side and top perspective view being a mirror image thereof.

In the drawing views, the tires, emblems, written matter and wheels shown in the broken lines are for illustrative purposes only and form no part of the claimed design.
